United States Patent Office

Des. 180,135
Patented Apr. 23, 1957

180,135

AIRPLANE

John T. Calhoun, Wichita, Kans., assignor to Beech Aircraft Corporation, Wichita, Kans., a corporation of Delaware

Application February 13, 1956, Serial No. 40,143

Term of patent 14 years

(Cl. D71—1)

Fig. 1 is a top plan view of an airplane embodying my new design;

Fig. 2 is a side elevation; and

Fig. 3 is a front view thereof.

The essential features of my design reside in the portions shown in full lines.

I claim:

The ornamental design for an airplane, substantially as shown and described.
